[57] CLAIM

The ornamental designs for a bone milling burr shaft, as shown and described.

DESCRIPTION

FIG. 1 is a perspective view of a burr shaft showing our new design;

FIG. 2 is a right side elevational view thereof, the left side being a mirror image thereof;

FIG. 3 is a front elevational view thereof, the back being a mirror image thereof;

FIG. 4 is a bottom elevational view thereof;

FIG. 5 is a top elevational view thereof; and

FIG. 6 is a sectional view taken along line 6—6 of FIG. 3;

FIG. 7 is a perspective view of a burr shaft showing a second embodiment of our new design;

FIG. 8 is a right side elevational view thereof, the left side being a mirror image thereof;

FIG. 9 is a front elevational view thereof, the back side being a mirror image thereof;

FIG. 10 is a bottom elevational view thereof;

FIG. 11 is a top elevational view thereof; and

FIG. 12 is a sectional view taken along line 12—12 of FIG. 9;

FIG. 13 is a perspective view of a burr shaft showing a third embodiment of our new design;

FIG. 14 is a right side elevational view thereof, the left side being a mirror image thereof;

FIG. 15 is a front elevational view thereof, the back side being a mirror image thereof;

FIG. 16 is a bottom elevational view thereof;

FIG. 17 is a top elevational view thereof; and

FIG. 18 is a sectional view taken along line 18—18 of FIG. 15;

FIG. 19 is a perspective view of a burr shaft showing a fourth embodiment of our new design;

FIG. 20 is a right side elevational view thereof, the left side being a mirror image thereof;

FIG. 21 is a front elevational view thereof, the back side being a mirror image thereof;

FIG. 22 is a bottom elevational view thereof;

FIG. 23 is a top elevational view thereof; and

FIG. 24 is a sectional view taken along line 24—24 of FIG. 21.

A burr head is shown in broken lines in FIG. 1—5, 7—11, 13—17, and 19—24 to illustrate the environment of the invention but does not constitute a part of the invention.
